UNITED STATES PATENT OFFICE.

SIMEON S. JACKSON, OF BOSTON, MASSACHUSETTS. ASSIGNOR TO THE STAFFORD COMPANY, OF BOSTON, MASSACHUSETTS, A CORPORATION OF MASSACHUSETTS.

PICKER-STICK CHECK FOR LOOMS.

Application filed July 27, 1925. Serial No. 46,196.

To all whom it may concern:

Be it known that I, SIMEON S. JACKSON, a citizen of Great Britain, residing at Hyde Park, Boston, in the county of Suffolk, 5 State of Massachusetts, have invented a certain new and useful Improvement in Picker-Stick Checks for Looms, of which the following is a specification, reference being had therein to the accompanying drawings.

10 The invention has relation to picker-stick checks for looms; that is to say, to devices employed in looms for bringing the picker-stick of a loom to rest, without excessive shock, at the completion of its travel inward 15 and outward. The invention consists in an improved and novel device of this class, embodying in a novel construction the familiar principle of a flexible check-strap formed into a loop which is disposed horizontally in practice, and within which the picker-stick vibrates or swings in its alternate movements, inward in a loom to propel the shuttle across the latter, and outward under the impact of a shuttle as the latter 25 completes its flight across the loom from the opposite side of the latter.

An illustrative embodiment of the invention is represented in the accompanying drawings, in which latter,—

30 Fig. 1 shows in rear elevation a picker-stick check embodying the invention, in connection with portions of a loom-lay and a picker-stick.

Fig. 2 is a bottom view of the parts that 35 are shown in Fig. 1.

Fig. 3 is a view in section on line 3—3 of Fig. 2 of the check device.

As in the case of other check devices of the same class, my improved check comprises a hanger 1 that is adapted to be secured to the lay-beam 2 of a loom, and a strap 3 which, as aforesaid, is formed into a loop that is disposed horizontally in the loom in which the device is employed, so 45 that the picker-stick 4 shall be enclosed within the said loop and in its working shall engage with the opposite bends or turns of such loop alternately. The hanger 1 is shown as attached to the lay-beam 2 by means of a bolt 5 engaging with an up- 50 standing ear 11 of the hanger, such ear being applied against a vertical surface at the rear of the lay-beam. To provide for adjustment of the device transversely of the loom, when such adjustment is found to be

necessary, the opening 16 in the hanger ear for the accommodation of the bolt, is in the form of a transverse slot.

One end-portion of the strap, namely that with which the back of the picker-stick 4 makes contact as the picker-stick is forced outward by the shuttle entering the corresponding shuttle-box, is in free swinging engagement with a pintle 6 with which the hanger 1 is provided. Such end-portion is 60 provided with an eye 7 which fits upon the said pintle and is adapted to turn there-around. The other end-portion of the strap, namely that portion with which the picker-stick engages as it completes its inward 65 movement in throwing the shuttle, is reversely bent into substantial parallelism with the intermediate length of the strap, and fixedly engaged with the hanger, in this instance by means of a bolt 8 and a clamping plate 9. This reversely-bent end-portion is interposed between the clamping plate and the body of the hanger, and the end of said plate which extends into the adjacent bend or loop of the strap is itself 70 bent or curved, forming a curved lip to avoid sharp bending of the strap around such end, and injury to the strap. The eye 7 at the other end of the strap is formed by doubling back and fastening the material 75 of the strap, preferably around a bushing of metal or fiber. The axis of the pintle is disposed vertically. The pintle in this instance is constituted by the upturned end-portion of an L-shaped member, the horizontally extending stem of which occupies a 80 socket in a boss or hub 13 that is formed upon the hanger. The said member is fixed in place, with capacity for adjustment of the pintle and corresponding end of the 85 strap transversely of the loom. In this instance a binding screw 14 applied in connection with the said boss or hub engages with the said stem to maintain it in adjusted position.

100 Preferably I combine with the strap means operating to resist longitudinal movement of the strap in either direction, to assist in bringing the picker-stick to rest. In the illustrated embodiment of the invention, I 105 employ a movement-resisting device which acts through frictional engagement with the intermediate portion of the length of the strap. This device comprises a bracket 15 secured to the lay-beam and having three 110

downwardly extending fingers 12, 12, 12, substantially in the same plane, through which the check-strap is run as shown in the drawings, so that the successive fingers 5 stand alternately on opposite sides of the strap and cause the latter to be bent around them in such manner as to cause considerable friction when the strap is moved lengthwise through the device. An important 10 function subserved by the device is that of holding open the loop formed by the check-strap. Still another function is that of guiding the intermediate length of the strap so as to obviate to a considerable extent the 15 tendency of the strap to cause displacement of the picker-stick at right angles to the direction of movement of the stick, during the checking action.

What is claimed as the invention is:—

- 20 1. A picker-stick check for looms comprising a hanger adapted to be mounted upon the lay-beam of a loom, a pintle carried by said hanger, and a check-strap forming a horizontal loop within which a picker-stick may move back and forth, said strap having at one end thereof an eye which fits upon the said pintle and is adapted to turn therearound so as to permit the adjacent portion of the strap to swing relative to the pintle, and said strap having the opposite end-portion thereof reversely bent into substantial parallelism with the intermediate length of the strap and fixedly engaged with the hanger.
- 25 2. A picker-stick check for looms comprising a hanger adapted to be mounted upon the lay-beam of a loom, a pintle carried by said hanger, a check-strap forming a horizontal loop within which a picker-stick may move back and forth, said strap having at one end thereof an eye which fits upon the said pintle and is adapted to turn therearound so as to permit the adjacent portion of the strap to swing relative to the pintle, with the opposite end-portion of the strap reversely-bent into substantial parallelism with the intermediate length of the strap and fixedly engaged with the hanger, and movement-resisting means coacting with the said intermediate lengths.
- 30 3. A picker-stick check for looms comprising a hanger adapted to be mounted upon the lay-beam of a loom, a pintle carried by said hanger, a check-strap forming a horizontal loop within which a picker-stick may move back and forth, said strap having at one end thereof an eye which fits upon the said pintle and is adapted to turn therearound so as to permit the adjacent portion of the strap to swing relative to the pintle, and the said strap having the opposite end-portion thereof reversely bent into substantial parallelism with the intermediate length of the strap, and a clamp by which the reversely-bent end-portion of the strap is made fast to the hanger.
- 35 4. A picker-stick check for looms comprising a hanger adapted to be mounted upon the lay-beam of a loom, a pintle carried by said hanger, a check-strap forming a horizontal loop within which a picker-stick may move back and forth, said strap having at one end thereof an eye which fits upon the said pintle and is adapted to turn therearound so as to permit the adjacent portion of the strap to swing relative to the pintle, with the opposite end-portion of the strap reversely-bent into substantial parallelism with the intermediate length of the strap and fixedly engaged with the hanger, and movement-resisting means coacting with the said intermediate lengths.
- 40 5. A picker-stick check for looms comprising a hanger adapted to be mounted upon the lay-beam of a loom, a pintle carried by said hanger, a check-strap forming a horizontal loop within which a picker-stick may move back and forth, said strap having at one end thereof an eye which fits upon the said pintle and is adapted to turn therearound so as to permit the adjacent portion of the strap to swing relative to the pintle, with the opposite end-portion of the strap reversely bent into substantial parallelism with the intermediate length of the strap and fixedly engaged with the hanger, and means coacting with the said intermediate length, serving to guide the same and resist its movement under the blows of the picker-stick.

ing a hanger adapted to be mounted upon the lay-beam of a loom, a pintle carried by said hanger, a check-strap forming a horizontal loop within which a picker-stick may move back and forth, said strap having at one end thereof an eye which fits upon the said pintle and is adapted to turn therearound so as to permit the adjacent portion of the strap to swing relative to the pintle, and the said strap having the opposite end-portion thereof reversely bent into substantial parallelism with the intermediate length of the strap, a clamping plate between which and the hanger the reversely-bent end-portion of the strap is entered, and a securing bolt for the said plate.

4. A picker-stick check for looms comprising a hanger adapted to be mounted upon the lay-beam of a loom, a pintle carried by said hanger, a check-strap forming a horizontal loop within which a picker-stick may move back and forth, said strap having at one end thereof an eye which fits upon the said pintle and is adapted to turn therearound so as to permit the adjacent portion of the strap to swing relative to the pintle, with the opposite end-portion of the strap reversely-bent into substantial parallelism with the intermediate length of the strap and fixedly engaged with the hanger, and movement-resisting means coacting with the said intermediate lengths.

5. A picker-stick check for looms comprising a hanger adapted to be mounted upon the lay-beam of a loom, a pintle carried by said hanger, a check-strap forming a horizontal loop within which a picker-stick may move back and forth, said strap having at one end thereof an eye which fits upon the said pintle and is adapted to turn therearound so as to permit the adjacent portion of the strap to swing relative to the pintle, with the opposite end-portion of the strap reversely bent into substantial parallelism with the intermediate length of the strap and fixedly engaged with the hanger, and means coacting with the said intermediate length, serving to guide the same and resist its movement under the blows of the picker-stick.

SIMEON S. JACKSON.
